UNITED STATES PATENT OFFICE.

JAMES B. PATTERSON, OF PHILADELPHIA, PENNSYLVANIA.

SUSPENSION-COUCH.

No. 869,142.

Specification of Letters Patent.

Patented Oct. 22, 1907.

Application filed August 8, 1907. Serial No. 387,630.

To all whom it may concern:

Be it known that I, JAMES B. PATTERSON, a citizen of the United States, residing at the city of Philadelphia, in the county of Philadelphia and State of Pennsylvania, have invented a certain new and useful 5 Suspension-Couch, of which the following is a specification.

Objects of the present invention are to provide a suspension couch or seat which will be ornamental, comfortable, light, attractive and capable of use as a piece of porch or outdoor furniture; to provide for keeping the body of the couch stretched tight and in comfortable position; to arrange for adjusting the height of the couch; and to provide a structure and arrangement of 15 parts by which these various objects are attained at a comparatively small cost and with an ornamental appearance.

In the accompanying drawings which illustrate what I believe at this time to be the best embodiment of my 20 invention Figure 1, is a view, partly in central section, of a couch embodying features of the invention. Fig. 2, is a perspective view of the frame of the couch. Fig. 3, is a transverse sectional view of a couch embodying features of the invention. Figs. 4 and 5, are similar 25 views illustrating modifications, and Fig. 6, is a perspective view drawn to an enlarged scale of means for adjustably supporting the couch.

In the drawings the end pieces 1, and side pieces 2, make up a rectangular frame for the body or seat of the 30 couch. As shown these pieces are of triangular cross-section which affords a maximum of strength for a minimum of material and they can be made by cutting ordinary material so that a piece of rectangular section can be made into two pieces of triangular section. At the 35 corners the pieces are permanently or detachably connected. 3, are castings or plates suitable for this purpose. At the ends of the frame there are hooks 4, and these hooks may be made part of the castings or plates 40. The pair of hooks at each end of the frame engage poles or rods 5. The material 6, which may be hammock cloth, passes over the frame and under each of the 45 poles or rods 5, and at each end is connected with a spreader 7, to which are connected clue cords 8, radiating from a suspension ring 9. The ends of the cloth 6, may be provided with pockets for the reception of the spreaders 7, and the clue cords may be attached to the spreaders and to the cloth by clips 10, shown in Figs. 3 and 5. At the sides the cloth 6, may be provided with pockets 11, Fig. 3, for the reception of the side pieces 2. As shown in Fig. 4, the cloth is shown as

passed around the outside of the pieces 2, and then laced together. For this purpose a lacing 12, may be employed and it can be passed through the loops or bunches of loops of the wefts at the selvages. 55

As shown in Fig. 5, the selvages are provided with pockets within which are inserted spreaders or rods 13, to which clips 10, are connected, and a lacing 14, is run through the eyes of the clips. 60

15, is a valance secured to the edges of the cloth 6, and arranged so as to hang down from the frame.

If desired the portions 16, of the cloth 6, may be upholstered or otherwise provided with pillows and the ends of the poles or rods 5, as well as the hooks 4, may be 65 variously ornamented so as to present an attractive appearance.

When weight is put upon the couch it is evident that the cloth 6, is tightly stretched across the frame by reason of the presence and arrangement of the poles or rods 70 5. Furthermore the cloth and frame can be conveniently and readily connected and disconnected and the frame itself can be readily assembled if it should be shipped in separate pieces. Each of the suspension rings 9, is provided with a loop 17, and with two bars 19 75 and 20, between which a pivotal tongue 21, is arranged so as to normally bite and hold the suspension cord 22, and yet be capable of being turned so as to release the same whereby the couch may be easily hung up and 80 taken down and also adjusted both as to height and as to horizontal position.

What I claim is:

1. A suspension couch comprising a frame provided at its ends with poles or rods, and a cloth arranged above the frame and under the poles or rods and provided at its 85 ends with suspension devices, substantially as described.

2. A suspension couch comprising a frame provided at its ends with poles or rods, a cloth arranged above the frame and under the rods or poles, spreaders at the ends of the cloth, and suspension rings having clue cords connected with said spreaders, substantially as described. 90

3. A suspension couch comprising a frame provided with rods or poles at its ends, a cloth arranged above the frame and under the poles or rods, clue cords connected with the ends of the cloth, suspension cords, and suspension eyes connected with the clue cords and provided with bars and a movable tongue between which the suspension cords are detachably engaged, substantially as described. 95

4. A suspension couch comprising a rectangular frame consisting of side and end pieces, rods or poles at the ends of the frame, a cloth arranged above the frame and under the poles or rods and attached to the side pieces, and suspension means at the end of the cloth, substantially as described. 100

5. A suspension couch comprising a rectangular frame 105 consisting of side and end pieces, rods or poles at the

- ends of the frame, cloth arranged above the frame and under the rods or poles, suspension devices at the ends of the cloth, and a lacing between the edges of the cloth and below the frame, substantially as described.
- 5 6. A suspension couch comprising a rectangular frame having side pieces, a cloth arranged above the frame and having at its edges and beneath the frame spreaders, and a lacing connecting the spreaders, substantially as described.
- 10 7. A suspension couch comprising a rectangular frame consisting of side and end pieces, plates or castings pro-

vided with hooks and adapted to connect said pieces at the corners of the frame, poles or rods engaged by the hooks and arranged at the ends of the frame, a cloth arranged above the frame and under the rods or poles, and 15 suspension devices for the ends of the cloth, substantially as described.

In testimony whereof I have hereunto signed my name,
JAMES B. PATTERSON.
